UNITED STATES PATENT OFFICE.

JAMES L. HICKEY, OF MILWAUKEE, WISCONSIN.

JACK.

Application filed December 11, 1922. Serial No. 606,326.

To all whom it may concern:

Be it known that I, JAMES L. HICKEY, a citizen of the United States, and a resident of Milwaukee, in the State of Wisconsin, 5 have invented certain new and useful Improvements in Jacks, of which the following is a specification.

This invention relates to improvements in means for progressively moving objects and 10 finds its main adaptation in jacks, etc.

One of the objects of my invention is to provide a simple, efficient and inexpensive device of this character designed to be serviceable as an ordinary jack and also for nipping purposes as used in railroad construction work for the purpose of holding a tie 15 up to the rail until it is spiked.

Another object of my invention is to provide means for lifting or lowering objects 20 having provision for pulling out spikes and also having provision for getting readily under heavy objects lying close to the ground.

A still further object of my invention is 25 to provide a combined or interchangeable jack and nipper such as may be used advantageously in connection with moving heavy machinery, riggers, pile drivers' operation, erectors and other heavy objects, and in all 30 cases where the conventional lifting jack in use will not get under anything close to the ground.

A still further object of my invention is to provide a device easily and simply constructed 35 and assembled in position designed to accelerate the downward movement of the weight lifting part or parts of my invention so that gravity may be effective to provide a quicker means of moving the lifting part 40 or parts than the mechanical means employed in my invention.

With the above and other objects in view my invention consists in the combination, arrangement and details of construction 45 closed in the drawings and specification, and then more particularly pointed out in the appended claims.

In the drawings, wherein similar reference numerals designate similar parts throughout 50 the several views,

Figure 1 is an end elevation of my invention,

Figure 2 is a front elevation thereof,

Figure 3 is a top plan view thereof,

55 Figure 4 is a cross-sectional view thereof,

Figure 5 is a view in elevation of my invention, partly in section,

Figure 6 is another end elevation of my invention,

Figure 7 is a view similar to Figure 6 but showing the rail shifters to be described in operative position,

Figure 8 is a fragmental vertical elevation, partly in section,

Figure 9 is a fragmental detail view partly in section showing the pawls in engagement with the racks,

Figure 10 is an end view of a pivot to be described,

Figure 9^A is a view similar to Figure 9 but showing the pawls disengaged from the rack,

Figure 11 is a fragmental sectional view showing the dovetailed connection between 75 upright and shifter, and

Figure 12 is a fragmental detail view of a platform shank.

Referring to the drawings which are merely illustrative of my invention 1 designates a 80 base support for a frame consisting of the parallel oppositely-arranged uprights 4 and 5 having a strut connection at 2 and 3 respectively with said base support 1. The opposite outer edges of the uprights are pro-

vided with jagged surfaces or teeth forming thereby longitudinal racks 5', it being noticed that the rack teeth on one edge of an upright are disposed in staggered relation with respect to those on the opposite edge. The inner sides 90 of the uprights carry the tracks or longitudinal rails 6 and 7 upon which slidably straddle the slides 8 and 9 formed with outwardly projecting pivots 10 and 11 which are cylindrical in outline, the terminals of which 95 pivots 12 and 13 being polygonal in shape. Before the uprights 4 and 5 are secured to the base support 1 one slide 8 is placed in position to slide upon one rail say, 8; a block forming part of a movable carriage or platform support and designated 19 has a lateral opening (not designated) into which partly projects one pivot, say 10 so that terminal 12 of this pivot protrudes centrally in opening 14 formed in a shank 15 carrying on 105 its upper end a platform 17, this shank 15 projecting thru a relatively long slot 16 formed centrally in the block 19; now the other polygonal terminal 13 of pivot 11 is next inserted into opening 14 of shank 15, 110 and then the upright 5 is pushed up close towards the upright 4, and thereupon it will

be seen that shank 15 is positioned in an upright manner in vertical or longitudinal alinement with slides 8 and 9, so as to insure a strictly vertical movement of this plat- 5 form support or carrying shank 15 at all times. The jack head or platform 17 comes to rest upon the top beam 18 connecting the upper edges of uprights 4 and 5, and it is de- signed to move above this beam.

10 The block is thus mounted so as to have a pivotal mounting and connection upon the pivots 10 and 11 of the slides 8 and 9 which run upon the rails 6 and 7. The block 19 is formed with a downwardly extending 15 arm 21 which is formed with a rightangular claw 22 having preferably a slitor notch 23 adapted to serve as a spike puller. The opposite end of the block may be made in various shapes as may be best found suitable in ordinary practice. It is designed to provide a handle 20 of suitable length and curvature as a means of giving the proper leverage to the block 19; the handle is shown by way of illustration as made in one 20 piece with the block altho it is within the range of my variable construction to form a sleeve upon the block and let the handle fit therein. These and other changes are intended to be covered. A pair of U-shaped 25 pawls or bails are provided to ride upon the racks. One bail consists of the rod 24 having the outwardly converging limbs 25, 26 connecting the transverse rung 27 which is pivoted at one end of the block 19. The 30 other bail is similarly shaped having the rod 24' with converging limbs 25', 26' ending in the transverse rung 27' pivoted to the opposite end of block 19. The rods 24, 24' are preferably made longer than rods or 35 rungs 27, 27' and these rods 27, 27' are the parts that enter successively the teeth of the racks 5', being held yieldably and slidably within these notches or racks 5' under influence of contractile springs 28 and 29 the 40 ends of which are attached directly to the rods 24, 24' of bails, it being also noticed that one bail is preferably made slightly longer than the other and so that when either rod 24, or 24' of either bail is within 45 one notch of the rack the other is within the next higher notch in staggered relation to the first notch. The bails also converge downwardly in the direction of the racks, and the block is in horizontal position when the 50 bails occupy the position shown in Figure 5. Now by taking hold of the actuating handle 20 on the block 19 and raising the same this act will also raise the bail having the rod 24 as shown in dotted lines in Figure 5, the other bail having the rod 24' 55 serving as a prop to allow such raising of the first-named bail. The action of springs 28 and 29 is to draw both bails forcibly against the notches 5' so as soon as the bail 60 has been raised sufficiently high it automati-

cally springs or snaps into another notch 5'; now this bail thus positioned acts as a prop for the other bail and this time the handle is taken hold of and swung downwardly so as to raise the bail having the rod 24' which 70 will automatically take into the next higher notch and in this manner the platform and block will both be raised or lowered accordingly as the handle is moved upwardly or downwardly, and in this manner a pawl 75 and ratchet or pawl and rack mechanism is had whereby a step by step movement is imparted to the carriage for working it up and down.

It is desired to provide for a quick release of the platform so as to dispense with the working of the platform downwardly step by step. This is accomplished in my invention by means of the erect upright rails or shifters 30 and 31 which are located upon one upright 4, and carry integral dovetail tenons 36 slidably mounted in dovetail runways or grooves 37 disposed horizontally of the said upright. The contractile springs 37 hold these shifters in retracted position so 90 their outer longitudinal edges will clear the inner parts of notches or rack teeth 51, 51'. There is a shaft 32 suitably mounted in upright 4 and carries a two-lobed cam 33 the lobes of which are out of engagement with the shifters when the rails 30, 31 are out of engagement with the pawls or bails. A crank handle 34 turns the shaft 32 and brings the lobes of cam 33 into a gradually 95 reaching horizontal position and this cam 100 will at the same time spread out the rails 30, 31 which ride in the grooves 37 so the outer edges of these rails force rods 24, 24' of the bails out of the notches and allow these rods to slide down the outer edges of 105 the rails 30, 31 so gravity may accelerate the downward movement of the carriage with platform 17 and claw 22. The rails 30, 31 move against the bails in spreading out relation against the tension of springs 35 so 110 by bringing the crank back to its normal horizontal position the springs 35 will pull back rails 30, 31 and allow the bails to automatically reenter the notches of the racks. The claw 22 of course serves as a nipper for 115 elevating heavy work and is optional and may be omitted and the platform 17 goes under any object just like an ordinary jack. The notch 23 in claw 22 will allow a spike being held therein in the act of ejecting 120 same.

All modifications within scope of claims are claimed herein.

What I desire to claim and secure by Letters Patent is:—

1. A jack comprising a base and two opposed substantially vertical uprights, parallel vertical guides on the inner faces of said uprights, each of said uprights having ratchet teeth projecting from its opposite 130
